MIXED FURYL-ALKYL KETONES

Anderson W. Ralston and Carl W. Christensen,
Chicago, Ill., assignors to Armour and Company, Chicago, Ill., a corporation of Illinois

No Drawing. Application April 23, 1935,
Serial No. 17,875

4 Claims. (Cl. 260—54)

This invention relates to mixed ketones and it comprises, as new compounds, ketones having the generic structure

wherein R is a furyl radical and R' is an alkyl radical having five or more carbon atoms.

The higher fatty acids, and by that we mean 10 those fatty acids derived from vegetable and animal oils and fats are extremely abundant materials and can be obtained at little expense. They have never, however, been used to any great extent as raw materials for the synthesis of more 15 valuable substances. These fatty acids have been used almost exclusively in the soap industry, for making candles, etc., and in but relatively few instances have they been used as raw materials in what might be termed the "fine" organic 20 chemical field.

We have now discovered a new class of compounds which can be made from the higher fatty acids and which have chemical and physical properties of marked technical and commercial 25 interest. We have discovered that the higher fatty acid chlorides, such as stearyl chloride, myristyl chloride, lauryl chloride, caproyl chloride, and other acid chlorides derived from, and corresponding to the higher fatty acids, can be 30 made to react with furane, or substituted furanes, to give mixed ketones having substituted properties which suit them for use in many technical 35 applications. Many of these mixed ketones are waxy solids and can be crystallized from organic solvents such as benzene, alcohol and others, to give pure ketones. The crystalline products, when melted and allowed to cool, yield substances of clearly defined "waxy" character, appearance 40 and "feel". Others are very high boiling liquids. 45 We have discovered that they are excellent dielectrics and can be used in electrical insulation. We have also discovered that these new substances are desirable constituents in waxing and polishing compounds. When added to lubricating 50 oils, the ketones of the present invention confer beneficial properties on the oil.

In its broad aspects, our invention comprises new products having the generic formula

wherein R is a furyl radical which may be substituted or not, and R' is an alkyl radical containing the alkyl residue of a higher fatty acid. Thus, as an example, one of the new products

falling within the scope of our invention is furyl heptadecyl ketone, which can be written structurally as follows:

In this case the C_7H_{15} , or heptadecyl radical, is the alkyl residue of stearic acid, $\text{C}_7\text{H}_{15}\text{COOH}$. This particular ketone has a melting point of 10 52.5—54° C.

Other typical ketones falling within the scope of our invention are: furyl undecyl ketone, boiling at 165—167° C. at 5 mm. pressure, and methyl furyl heptadecyl ketone melting at 68—69° C. and 15 having the formula:

The dibenzofuryl compounds are especially interesting and valuable materials. Dibenzofuryl heptadecyl ketone melts at 83—84° C. and has the 25 formula:

The corresponding undecyl compound melts at 30 74—75° C.

All of the ketones of our invention can be made by the Friedel-Crafts reaction or by the 35 Grignard synthesis. We find that the Friedel-Crafts gives high yields.

Thus, for example, when we wish to make dibenzofuryl heptadecyl ketone, we start with dibenzofuran and stearyl chloride. The stearyl 40 chloride can be made in any of the known ways from stearic acid. Generally the stearic acid is reacted with phosphorous pentachloride or other chlorinating agent commonly used for converting aliphatic carboxylic acids to their corresponding acid chlorides. We then prepare a mixture containing about 29 parts by weight of stearyl chloride, 16 parts by weight of dibenzofuran and about 200 parts by weight of carbon disulphide. This mixture is cooled in an ice bath and about 50 26 parts of aluminum chloride (dry) are slowly added with stirring until there is no further evolution of hydrochloric acid. The reaction mixture is then poured into a mixture of ice and dilute hydrochloric acid to hydrolyze the complex 55

aluminum compound formed in the reaction. Finally the resulting acid mixture is placed in a flask and subjected to steam distillation. This removes carbon disulphide and any excess of dibenzofuran. During the steam distillation, the dibenzofuryl heptadecyl ketone separates from the aqueous reaction mixture in the distilling flask as an oily supernatant liquid. It does not distil over with the carbon disulphide and can be separated from the aqueous solution of aluminum chloride in the distilling flask by simple decantation. It is then taken up in acetone, carbon tetrachloride or other organic solvent and crystallized therefrom.

In a similar manner we can start with furane, alkyl-substituted furanes and other substitution products. Likewise, as stated, we can start with any acid chloride of the higher fatty acids. Generally we start with the acid chlorides of fatty acids having twelve or more carbon atoms since these fatty acids are readily available and cheap. Our invention is therefore not limited to the specific compounds described above, since we are the first to describe mixed ketones in which one

radical attached to the carbonyl is a furyl radical, or its substitution products, and the other radical is the alkyl residue of a higher fatty acid. And by higher fatty acid we mean those acids having six or more carbon atoms.

Having thus described our invention what we claim is:

1. Mixed ketones having the structural formula

10

wherein R is a furyl radical and R' is an alkyl radical having at least five carbon atoms.

2. Mixed ketones having the structural formula

15

wherein R is a furyl radical and R' is an alkyl radical having at least eleven carbon atoms.

3. A furyl heptadecyl ketone.

4. A furyl undecyl ketone.
